FIG. 1

FIG. 2

FIG. 3

FIG. 4

INVENTOR
MABEL R. CHARLES
BY
A. B. Bowman
ATTORNEY

UNITED STATES PATENT OFFICE

MABEL R. CHARLES, OF SAN DIEGO, CALIFORNIA

LAMP

Application filed January 15, 1931. Serial No. 508,959.

My invention relates to lamps, more particularly to ornamental lamps, and the objects of my invention are:

First, to provide a lamp of this class which simulates a candle.

Second, to provide a lamp of this class forming in one unit the body of the candle and a representation of its flame in which the body portion emits a soft glow whereas the 10 flame representing portion emits a brighter light.

Third, to provide a lamp of this class which is so arranged that its size may be reduced to that of the old fashioned candle used 15 on Christmas trees and to provide a lamp which closely simulates the appearance of these candles when so arranged.

Fourth, to provide a lamp of this class which is particularly adapted for use in 20 candelabrum or other ornamental candle holding devices, and

Fifth, to provide on the whole a novelly constructed ornamental lamp which is durable, efficient in its action and which will not 25 readily deteriorate or get out of order.

With these and other objects in view as will appear hereinafter, my invention consists of certain novel features of construction, combination and arrangement of parts and portions 30 as will be hereinafter described in detail and particularly set forth in the appended claims, reference being had to the accompanying drawing and to the characters of reference thereon which form a part of this 35 application, in which:

Figure 1 is an elevational view of my lamp structure; Fig. 2 is an enlarged sectional view thereof with parts and portions as shown in elevation; Fig. 3 is a substantially diagrammatical view of lamp element with the lamp 40 shown in dotted lines; and Fig. 4 is a similar diagrammatical view of a slightly modified form of my lamp structure.

Similar characters of reference refer to 45 similar parts and portions throughout the several views of the drawing.

Body member 1, fitting 2, neck 3, head 50 member 4, conductor carrying member 1a, conductors 5 and 6, illuminating elements 7, illuminating element coil 8, illuminating ele-

ments 9 and conductor 10 constitute the principal parts and portions of my novel lamp.

The lamp structure includes a body member 1, which is formed of glass and which is hollow with the outward appearance of a candle as shown best in Fig. 1. At its lower end, the body member 1 is provided with a suitable fitting 2, which enables it to be secured to a conventional light socket. At the upper end of the body member 1, there is provided an upwardly extending integral short neck 3, which is preferably formed of a glass composition such as the body 1 but is solid as shown in Fig. 2.

Formed above the neck 3 is a head member 4, which is of glass and hollow like the body member 1. The head member 4 is shaped and colored so as to simulate a candle flame.

Extending into the lower end of the body member 1 is a conductor carrying member 1a, formed of glass integral with the body member 1. Cast in the carrying member 1a is a pair of conductors 5. These conductors 5 are connected in any suitable manner to the fitting 2. The conductor carrying member 1a also forms a means whereby air may be exhausted from the body member 1, and, if desired, inert gas substituted in place thereof.

A second pair of conductors 6 are cast in 80 the material of the neck 3 so that their ends extend into body member 1 and into the head member 4. Extending between the pairs of conductors 5 and 6, within the body member 1, are a pair of elements 7. As shown in Fig. 85

2, the elements 7 are straight. Within the head member 4, there is provided an illuminating element coil 8, the ends of which are connected to the corresponding ends of the conductors 6, thus providing a circuit in 90 which the illuminating elements 7 and coils 8 are in series. The element within the head member 4 is in the form of a coil by reason of the limited space and also for the purpose of intensifying the illumination. The air in 95 the head member 4 is exhausted through the tip thereof.

The glass of the body member 1 is preferably treated so as to be translucent or opalescent in order to simulate the waxy nature 100

of the candle body. If it is desired to further reduce the illumination in the body member 1, as compared to that in the head member 4, this may be accomplished by substituting 5 illuminating elements 9 in place of the illuminating elements 7, the latter elements having less resistance than the coil 8, so that when the coil is giving off a bright light, the elements 9 are merely glowing.

10 Substantially the same effect can be accomplished in another manner as indicated diagrammatically in Fig. 4. With this structure, a conductor 10, which extends from the carrying member 1a to the head member 4, is substituted 15 in place of one of each pair of conductors 5 and 6, thus leaving only one illuminating element 7.

Though I have shown and described a particular construction, combination and arrangement of parts and portions, and certain modifications thereof, I do not wish to be limited to this particular construction, combination and arrangement, nor to the modification thereof, but desire to include in 25 the scope of my invention the construction, combination and arrangement substantially as set forth in the appended claims.

Having thus described my invention, what I claim as new and desire to secure by Letters 30 Patent is:

1. In a lamp structure, a hollow body member, fitting means at one end of said body member for connecting the same to a source of electrical energy, a hollow head member, a 35 solid neck member joining said head member to said body member, conductors cast in said neck member and communicating between said head member and said body member, an illuminating element connected with said fitting means and joined to said conductors, and an illuminating means within said head member joining said conductors.

2. In a lamp structure, a hollow body member, fitting means at one end of said body 45 member for connecting the same to a source of electrical energy, a hollow head member, a solid neck member joining said head member to said body member, conductors cast in said neck member and communicating between 50 said head member and said body member, an illuminating element connected with said fitting means and joined to said conductors, and an illuminating means within said head member joining said conductors, said body 55 member having a lesser transparency than said head member whereby the density of light emitted by said body member is less than that emitted by said head member.

3. In a lamp structure, a hollow body member, fitting means at one end of said body member for connecting the same to a source of electrical energy, a hollow head member, a solid neck member joining said head member to said body member, conductors cast in said 65 neck member and communicating between

said head member and said body member, an illuminating element connected with said fitting means and joined to said conductors, and an illuminating means within said head member joining said conductors, said illuminating element having a lesser resistance than said illuminating means whereby the density of light emitted thereby is less than that emitted by said illuminating means.

4. In a lamp structure, a hollow body member, fitting means at one end of said body member for connecting the same to a source of electrical energy, a hollow head member, a solid neck member joining said head member, to said body member, conductors cast in said neck member and communicating between said head member and said body member, an illuminating element connected with said fitting means and joined to said conductors, and an illuminating means within said head member joining said conductors, said body member having a lesser transparency than said head member, and said illuminating element arranged to emit a light of lesser density than said illuminating means, whereby the intensity of light given off by said body member is less than that given off by said head member.

5. In a lamp structure, a sealed hollow body member, a separately sealed hollow head member formed integrally with said body member, a sealed hollow head member extending from a portion of the wall of said body member, a conductor extending through said body member, the one end thereof terminating within said hollow head member, a second conductor extending into said body member, a third conductor extending between said body member and said head member, an illuminating element within said body member connecting said second and third conductors, an illuminating means within said head member connecting said first and third conductors, and a fitting for connecting said first and second conductors to a source of electrical energy.

6. In a lamp structure, a hollow body member formed to simulate a candle and closed at both ends, a head member integrally attached to one end of said body member, sealed therefrom and formed to simulate a candle flame, conductors communicating between said head member and said body member, other conductors extending through the end of said body member opposite from said head member and illuminating elements within said head member and body member.

7. In a lamp structure, a hollow body member formed to simulate a candle and closed at both ends, a head member integrally attached to one end of said body member, sealed therefrom and formed to simulate a candle flame, conductors communicating between said head member and said body member, other conductors extending through the end

of said body member opposite from said head member and illuminating elements within said head member and body member, said body member having less translucency than
5 said head member, whereby the light emitted by said body member has less density than that emitted from said head member.

8. In a lamp structure, a hollow body member formed to simulate a candle and closed at
10 both ends, a head member integrally attached to one end of said body member, sealed therefrom and formed to simulate a candle flame, conductors communicating between said head member and said body member, other conductors
15 extending through the end of said body member opposite from said head member, and illuminating elements within said head member and body member, the illuminating element within said head member being arranged
20 to emit a light of greater density and concentration than that emitted by the illuminating element within said body member.

In testimony whereof, I have hereunto set my hand at San Diego, California this 9th
25 day of January 1931.

MABEL R. CHARLES.
